SAFETY STOP FOR SHADE ROLLERS

Leonard P. Weber, Omaha, Nebr., assignor of
forty per cent to Fred B. Wallace, Omaha,
Nebr.

Application November 6, 1934, Serial No. 751,771

1 Claim. (Cl. 156—36)

This invention appertains to new and useful improvements in shade rollers and more particularly to means for association with a roller so that it may be adjusted to prevent the raising of the lower end of the curtain above a given height.

A principal object of the present invention is to provide a curtain roller wherein the roller is provided with stop means limiting the height to which the free end of the curtain can ride, thus preventing the flying up and wrapping around of the curtain, which frequently happens when the curtain slips out of the operator's hand.

Other important objects and advantages of the invention will become apparent to the reader of the following specification.

In the drawings:

Figure 1 represents a fragmentary elevational view of a window frame showing the curtain and roller applied.

Figure 2 represents a fragmentary side elevational view of the roller.

Figure 3 represents an enlarged fragmentary longitudinal sectional view.

Figure 4 represents a cross sectional view taken substantially on line 4—4 of Figure 3.

Figure 5 represents a fragmentary longitudinal sectional view through one end of the roller showing the mechanism in elevation.

Figure 6 represents an end elevational view of the novel roller.

Referring to the drawings wherein like numerals designate like parts, it can be seen in Figure 1, that the numeral 5 represents a common style of wooden or metal window frame, while numeral 6 represents a curtain roll supported by the bracket 7 and on which is supported the curtain 8.

The roller 6 is improved at its pivot end, by providing a bore 8 in this end of the roller and inserting an elongated cylinder 10 therein having the end wall 11 at its inner end and the end wall 12 at its outer end. This cylinder 10 is provided with a pair of longitudinally extending slots 13, these slots being at diametrically opposite side portions of the cylinder. The cylinder is also provided with a pair of short slots 14—14 alined with the first mentioned slots.

In place of the usual pivot pin, an elongated

threaded member 15 forming a screw is provided, having a smooth portion 16 for journalled engagement through the end wall 11 of the cylinder. The outer end extends through the wall 12 and is provided with a disk 17 from which extends the pivot pin 18 of polygonal cross section.

A cap structure 19 having an inwardly disposed tubular portion 20 is secured to the roller 6 by suitable securing elements 21, it being seen in Figure 3 that the tubular portion is secured to the cylinder 10.

In the operation of the roller, the screw 15 is first adjusted so as to move the follower 22 in contact with the bumper 23, the follower 22 being provided with a threaded bore for receiving the screw 15 and lugs 24 riding in the grooves 13, while the bumper 23 is provided with a bore larger in diameter than the screw 15 and with lugs 25 for riding engagement in the short slots 14. A compressible coiled spring 26 is interposed between the end wall 12 of the cylinder 10 and the bumper 23.

With this adjustment, when the shade is pulled down, the follower travels away from the bumper 23, and in the event shade slips from operator's hand, the roller can only rotate back to point of contact between follower 22 and bumper 23.

While the foregoing specification sets forth the invention in specific terms, it is to be understood that numerous changes in the shape, size, materials may be resorted to without departing from the spirit or scope of the invention as claimed hereinafter.

Having described the invention, what is claimed as new is:

In a shade roller having a hollow end, a pivot pin for disposition into the said hollow end, a spring projected bumper in the hollow end, said pin being provided with threads, and a follower adapted to be fed by the said threaded portion of the pin being adapted to strike the said bumper to stop the roller, and guide means for the said follower, a barrel for receiving the pin and the stop and the follower and the spring, said barrel being provided with a longitudinal slot, and lugs on the stop and bumper for slidably disposition in the slot.

LEONARD P. WEBER.
